UNITED STATES PATENT OFFICE.

HANS L. LARSEN, OF CHICAGO, ILLINOIS.

OIL-CAN.

1,074,440.

Specification of Letters Patent.

Patented Sept. 30, 1913.

Original application filed July 25, 1912, Serial No. 711,564. Divided and this application filed December 23, 1912. Serial No. 738,195.

To all whom it may concern:

Be it known that I, HANS L. LARSEN, a citizen of the United States, and a resident of the city of Chicago, county of Cook, and 5 State of Illinois, have invented certain new and useful Improvements in Oil-Cans, of which the following is a specification.

My invention relates to improvements in oil cans, the present application being a division 10 of my pending application Serial No. 711,564, filed July 25, 1912, for oil cans.

The object of this invention is the production of an oil can which will be so constructed as to be adapted to be readily and easily 15 closed when not in use to prevent leakage therefrom.

A further object is the production of an oil can which will be durable and economical in construction.

20 Other objects will appear hereinafter.

The invention consists in the combinations and arrangements of parts hereinafter described and claimed.

The invention will be best understood by 25 reference to the accompanying drawings forming a part of this specification, and in which—

Figure 1 is a central vertical section of an oil can embodying my invention, and Fig. 2 30 is a top plan view thereof.

The preferred form of construction as illustrated in the drawings comprises a circular hollow body 1 provided with the usual convex bottom 2 adapted to be flexed when 35 desired in order to effect ejection of the oil from the can.

Provided centrally at the upper side of the body 1 is the spout of the can consisting of a threaded nipple 3 and a threaded cap 40 4 which releasably engages the nipple 3 as shown. The cap 4 is provided at its outer end with an outwardly projecting flange 5 the periphery of which is knurled in order to facilitate rotation thereof in attaching or 45 detaching the same. Provided in the outer end of the cap 4 is the oil discharge orifice 6. Formed at the lower or inner end of the cap 4 is a tapering seat 7 in which is removably arranged a closure 8 of corresponding 50 shape, formed preferably of cork.

With the arrangement disclosed it will be seen that when the closure 8 is in position in the seat 7 discharge through the spout of

the can will be effectually prevented. When it is desired to use the can it is only required 55 to detach the cap and remove the cork or stopper and then replace said cap, it being clear that after removal of said closure the can will operate in the usual manner.

The upper side of the body 1 is formed 60 with an annular channel 9 in which is arranged a wick or fabric spreader 10 adapted, when the can is in use, to effect spreading of the oil upon the surface upon which the oil has been discharged from the spout. 65

An oil can of the construction set forth is of simple construction and will be found effectual in use.

While I have illustrated and described the preferred form of construction for carrying 70 my invention into effect, this is capable of variation and modification without departing from the spirit of the invention. I, therefore, do not wish to be limited to the precise details of construction set forth, but 75 desire to avail myself of such variations and modifications as come within the scope of the appended claims.

Having described my invention what I claim as new and desire to secure by Letters 80 Patent is:

1. A device of the class described comprising a hollow body having a liquid chamber therein; a spout comprising a nipple projecting from said body; a cap engaging said nipple, said cap being formed at its center into a substantially conical spout having a central discharge orifice in its outer end; and a closure for said spout, substantially as described. 90

2. A device of the class described comprising a hollow body having a liquid chamber therein; a spout comprising a nipple projecting from said body; a cap engaging said nipple, said cap being formed at its center into a substantially conical spout having a central discharge orifice in its outer end; an upwardly tapering seat formed integral with the inner end of said cap; and a closure removably inserted in said seat to close said 100 spout, substantially as described.

3. A device of the class described comprising a hollow body having a liquid chamber therein; a spout comprising a threaded nipple projecting from said body; a threaded 105 cap engaging said nipple, said cap being

formed at its center into a substantially conical spout having a central perforation at its apex; an upwardly tapering seat formed integral with the inner end of said cap under said spout; and an upwardly tapering closure removably inserted into said seat to close spout, substantially as described.

In testimony whereof I have signed my name to this specification in the presence of two subscribing witnesses.

HANS L. LARSEN.
